CLAIM

The ornamental design for a cylindrical decorative element for a lamp, as shown and described.

DESCRIPTION

FIG. 1 is a perspective view of a cylindrical decorative element for a lamp showing my new design;

FIG. 2 is a front elevation view thereof; the rear elevation, left side, and right side views being identical;

FIG. 3 is a top plan view thereof;

FIG. 4 is a bottom plan view thereof;

FIG. 5 is an enlarged view of area 5 indicated in FIG. 1; FIG. 6 is a practical application view thereof on a lamp base with a lampshade thereon; and,

FIG. 7 is a practical application view thereof applied to a drop light base.

The broken lines shown in the drawings are for illustrative purpose only and form no part of the claimed design.
